Primary Examiner — Annette H Para*(74) Attorney, Agent, or Firm* — Dale Skalla**ABSTRACT**

A new garden type *Chrysanthemum* plant named 'CIFZ0091' particularly distinguished by its medium size plant with mound plant habit, small to medium sized decorative flowers with yellow flower color, and a natural season response early to mid-October.

1 Drawing Sheet**1**

Latin name of the genus and species of the plant claimed:
Chrysanthemum x morifolium.

Varietal denomination: 'CIFZ0091'.

BACKGROUND OF THE NEW PLANT

The present invention comprises a new *Chrysanthemum*, botanically known as *Chrysanthemum x morifolium*, and hereinafter referred to by the variety name 'CIFZ0091'.

'CIFZ0091' is a product of a planned breeding program. The new cultivar has a medium sized plant with mound plant habit, small to medium sized decorative flowers with yellow flower color, and a natural season response early to mid-October.

'CIFZ0091' originated from a cross made in February 2016 in Enkhuizen, The Netherlands. Seeds were sown in November 2016 in Gilroy, Calif. and 'CIFZ0091' was selected from the resulting population on Mar. 24, 2017 in Alva, Fla.

The female parent was 'PPP CON OR05', U.S. Plant Pat. No. 18,094

2

The male parent was one of a few possible varieties as the seedling came from a bulked seed lot containing more than one cross. These varieties share a number of characteristics, compared to 'CIFZ0091':

5

TABLE 2

	Trait	'CIFZ0091'	Unknown male
10	Natural response	Similar or two weeks slower	Similar or two weeks faster
	Blackcloth response	Similar or one week lower	Similar or one week faster
	Flower size:	Similar or a bit smaller	Similar or a bit larger
15	Flower color:	Yellow	Yellow or pink/lavender
	Flower type:	Less disc florets	More disc florets
	Plant habit:	Similar	Similar

The first act of asexual reproduction of 'CIFZ0091' was 20 accomplished when vegetative stem cuttings were propagated from the initial selection in June 2017 in Alva, Fla.

BRIEF SUMMARY OF INVENTION

25 Horticultural examination of plants grown from cuttings of the plant initiated in January 2017 and continuing thereafter, has demonstrated that the combination of characteristics as herein disclosed for 'CIFZ0091' are firmly fixed and are retained through successive generations of asexual reproduction.

'CIFZ0091' has not been observed under all possible environmental conditions. The phenotype may vary significantly with variations in environment such as temperature, light intensity and day length.

30 35 A Plant Breeder's Right for this cultivar has not yet been applied for. 'CIFZ0091' has not been made publicly available prior to the effective filing date of this application, notwithstanding any disclosure that may have been made less than one year prior to the effective filing date of this

TABLE 1

Characteristics of the female parent, compared to 'CIFZ0091':		
Trait	'CIFZ0091'	'PPP CON OR05'
Natural response:	As much as 3 weeks slower	As much as 3 weeks faster
Blackcloth response:	Similar	Similar
Flower size:	Similar or a bit smaller	Similar or a bit larger
Flower color:	Yellow	Orange
Flower type:	Similar	Similar
Plant size:	Bit larger	Bit smaller
Plant habit:	Wider/more mound	Rounder
Flower longevity:	Initial flower color holds	Initial flower color fades quickly after opening

application by the inventor or another who obtained 'CIFZ0091' directly from the inventor.

The following traits have been repeatedly observed and are determined to be basic characteristics of the new variety. The combination of these characteristics distinguishes this *Chrysanthemum* as a new and distinct variety.

BRIEF DESCRIPTION OF THE PHOTOGRAPHS

The accompanying photographic drawings show typical flower and foliage characteristics of 'CIFZ0091' with colors being as true as possible with an illustration of this type. The photographic drawings show in FIG. 1 a close view of flower of the new variety and in FIG. 2 a flowering plant from an outdoor trial.

The aforementioned photographs: FIG. 1, as well as FIG. 2 were taken on Sep. 8, 2021 both showing a plant from the same blackcloth outdoor trial in Enkhuizen, The Netherlands.

These plants were about 13 weeks of age. One rooted cutting per pot had been planted in a 19 cm pot, not pinched in week 23, 2021 and black clothed from week 29. Plants started flowering the end of August 2021.

The measurements were taken in Enkhuizen, The Netherlands, in September 2021 on plants from the same outdoor blackcloth trial.

DETAILED BOTANICAL DESCRIPTION

Color references are made to The Royal Horticultural Society Colour Chart (R.H.S.) 2001.

DIFFERENCES BETWEEN THE NEW VARIETY 'CIFZ0091' AND TWO MOST SIMILAR VARIETIES

TABLE 3

Trait	'CIFZ0091'	'CIFZ0034', U.S. Plant Pat. No. 29,258
Natural response:	Similar except faster in the north	Similar except slower in the north
Blackcloth response:	1 week faster	1 week slower
Flower size:	Smaller	Larger
Flower color:	Similar, more golden	Similar, more yellow
Flower type:	Similar	Similar
Plant size:	Similar	Similar
Plant habit:	Similar	Similar
Flower longevity:	Less frost damage/ longer lasting	More frost damage/ shorter lived

TABLE 4

Trait	CIFZ0091	'Zanmutang', U.S. Plant Pat. No. 23,615
Natural response:	Similar except with cool nights	Similar except with cool nights
Blackcloth response:	½ week faster	½ week slower
Flower size:	Similar or bit larger	Similar or bit smaller
Flower color:	Similar, bit more golden	Similar, bit more yellow
Flower type:	Similar	Similar
Plant size:	Larger	Smaller
Plant habit:	Similar	Similar

TABLE 4-continued

5	Trait	'CIFZ0091'	'Zanmutang', U.S. Plant Pat. No. 23,615
	Flower longevity:	Less frost damage/ longer lasting	More frost damage/ shorter lived
Plant:			
Form, growth and habit.—Herbaceous garden-type, stems Upright and outwardly spreading, freely branching, strong and moderately vigorous growth habit.			
Plant height (above soil).—22 cm.			
Plant height (inflorescence included).—24 cm.			
Plant width.—42 cm.			
Roots:			
Number of days to initiate roots.—About 4 days at about 22° C.			
Number of days to produce a rooted cutting.—14-16 days at 22° C.			
Type.—Fine, fibrous, free branching.			
Color.—RHS N155B.			
Foliage:			
Arrangement.—Alternate.			
Immature leaf, color upper surface.—RHS 137A.			
Immature leaf, color lower surface.—RHS 137B.			
Mature leaf, color, upper surface.—RHS 137A.			
Mature leaf, color lower surface.—RHS 137B.			
Length.—9 cm.			
Width.—6.0 cm.			
Shape.—Ovate, with distinct lobes.			
Base shape.—Attenuate.			
Apex shape.—Abruptly acute.			
Margin.—2-3 lobed.			
Number of margin indentations.—Approximately 20.			
Depth of margin indentations.—Deep.			
Leaf length terminal lobe relative to total leaf length.—Long.			
Leaf depth lower lateral sinus.—Short.			
Texture, upper surface.—Bifid hairs			
Texture, lower surface.—Bifid hairs.			
Color of veins, upper surface.—RHS 138A.			
Color of veins, lower surface.—RHS 138A.			
Pattern of veining.—Palmate.			
Petiole color.—RHS 138A.			
Petiole length.—1.5-2.0 cm.			
Diameter.—0.3 cm.			
Texture.—Bifid hairs.			
Presence of stipules.—Not present.			
55 Stem:			
Quantity of main branches per plant.—9.			
Color of stem.—RHS 146B.			
Length of stem.—9.0-10.0 cm.			
Diameter.—0.5 cm.			
Length of internodes.—1.5-4.0 cm.			
Texture.—Bifid hairs.			
Color of peduncle.—RHS 146A.			
Length of peduncle.—3.0-4.0 cm.			
Peduncle diameter.—0.2 cm.			
Texture.—Bifid hairs.			

Inflorescence:

Type.—Compositae, solitary, semi-double type inflorescences borne terminally above foliage, ligulate ray florets arranged in whorls on a capitulum giving a semi-double flower.

Quantity of short days to flowering (response time).—
Approximately 7 weeks.

Quantity of inflorescences per plant.—200 with several small buds developing.

Lastingness of individual blooms on the plant.—About five weeks from first color.

Fragrance.—Slightly spicy.

Bud (when showing color):

Color.—RHS 12A.

Length.—0.7 cm.

Width.—1.0 cm.

Shape.—Oblate.

Immature inflorescence (at moment of opening):

Diameter.—1.9 cm.

Color of ray florets, upper surface.—RHS 9A.

Color of ray florets, lower surface.—RHS 9B.

Mature inflorescence:

Diameter.—4.0 cm.

Depth.—2.0 cm.

Total diameter of disc.—0.8 cm.

Receptacle color.—RHS 138A.

Receptacle height.—0.5 cm.

Receptacle diameter.—1.4 cm.

Length of corolla tube.—0.2 cm.

Ray florets:

Average quantity of florets.—85 in several whorls.

Color of florets, upper surface.—RHS 9A.

Color lower surface.—RHS 9B.

Length.—1.8 cm.

Width/diameter.—0.4 cm.

Shape.—Oblong.

Apex shape.—Retuse.

Base shape.—Tube.

Margin.—entire: Small incisions may be present at tip.

Margin.—type of rolling: Weakly involute.

Texture, upper surface.—Papillate.

Lower surface.—Papillate.

Ribs present.—Yes.

Number of keels.—1.

Profile at widest point.—Flat.

Longitudinal axis shape.—Flat.

Longitudinal axis curvature strength.—No curve.

Corolla tube shape.—Circular.

Disc florets:

Number of disk florets.—50-70.

Width.—0.1 cm.

Length.—1.1 cm.

Color.—RHS 17A.

Inflorescence (at moment of senescence):

Color of ray florets, upper surface.—RHS 9A.

Color of ray florets, lower surface.—RHS 72B, spots

53A.

Phyllaries:

Quantity.—18-22.

Color, upper surface.—RHS 138A.

Color, lower surface.—RHS 138B.

Length.—0.7 cm.

Width.—0.2 cm.

Shape.—Lanceolate.

Apex shape.—Acute.

Base.—Fused.

Margins.—Entire.

Texture, upper surface.—Glabrous.

Texture, lower surface.—Canescent.

Reproductive organs:

Pistil.—One.

Length.—0.4 cm.

Style color.—RHS 5C.

Style length.—0.3 cm.

Stigma color.—RHS 9C.

Stigma shape.—Bi-parted.

Ovary color.—RHS 145D.

Ovary length.—0.2 cm.

Ovary width.—0.1 cm.

Androecium:

Stamens.—1, found on only disc florets.

Color of filaments.—RHS 157B.

Length filaments.—0.2 cm.

Anther color.—RHS 17A.

Anther length.—0.2 cm.

Anther shape.—Oval to club shaped.

Color of pollen.—RHS 17A.

Pollen amount.—Moderate.

Fertility/seed set.—Has not been determined to date.

Disease/pest resistance.—Has not been determined to date.

Hardiness.—Has not been determined to date.

What is claimed is:

- 45 1. A new and distinct variety of *Chrysanthemum* plant named 'CIFZ0091' substantially as illustrated and described herein.
